UNITED STATES PATENT OFFICE.

FRANK HOFFNER, OF NANTICOKE, PENNSYLVANIA.

FLYING MACHINE.

Application filed December 19, 1921. Serial No. 523,437.

To all whom it may concern:

Be it known that I, FRANK HOFFNER, a citizen of the United States, residing at Nanticoke, in the county of Luzerne and State of Pennsylvania, have invented a new and useful Flying Machine, of which the following is a specification.

The device forming the subject matter of this application is a flying machine, and the invention aims to provide a flying machine which is so constructed that it will take up very little space, measured horizontally, the machine, therefore being adapted to be operated in restricted places where an ordinary plane would be useless.

The invention aims, further, to provide a flying machine of the helicopter type, having means whereby components may be resolved out of the lifting force, thereby to move the machine forwardly or laterally.

It is within the province of the disclosure to improve generally and to enhance the utility of devices of that type to which the invention appertains.

In the drawings:—

Figure 1 shows in rear elevation, a device constructed in accordance with the invention; Figure 2 is a top plan; Figure 3 is a vertical longitudinal section wherein parts appear in elevation.

In carrying out the invention there is provided a frame 1 of considerably greater height than width, the frame being wider at its upper end than at its lower end. A cab 2 is mounted on the frame 1, an internal combustion engine 3 being disposed on the frame 1, within the cab. The radiator for the internal combustion engine 3 is denoted by the numeral 4 and is located in the front of the cab 2, the fuel tank being shown at 35.

Upwardly diverging shafts 5 are journaled in bearings 7 on the frame 1, the shafts being located on opposite sides of the frame as shown clearly in Figure 1. Lifting propellers 6 are secured to the upper ends of the shafts 5, the machine being essentially, of the helicopter type. The lower ends of the shafts 5 are connected operatively with the shaft 9 of the engine 3 by beveled pinions 8. A seat 10 is disposed within the cab 2 and is so located that the occupant can control the engine 3 readily.

Bearings 11 are mounted on the upper end of the frame 1, and in the bearings 11, a shaft 12 is journaled for rotation, the

shaft being disposed parallel to the line of advance of the craft, the line of advance being indicated by the arrow A in Figure 3. A rudder 14 is secured to the shaft 12 and is disposed parallel to the line of advance. The shaft 12 has a depending arm 15 connected by a link 16 to the arm 17 of a lever 18 fulcrumed on the side of the internal combustion engine 3 or elsewhere, the lever having a latch mechanism 19 adapted to cooperate with a segment 20 on the engine.

Hangers 21 depend from the top portion of the frame 1, as shown best in Figure 1, and in the hangers there is journaled a shaft 22, disposed at right angles to the line of advance of the craft. The shaft 22 carries a rudder 23 disposed at right angles to the line of advance of the craft. There is an arm 24 on the shaft 22, the arm being connected by a link 25 to an arm 26 on a shaft which is journaled in bearings 27 mounted on the upper end of the engine 3, the shaft carrying a hand wheel 28 which, like the lever 18, is readily accessible from the operator's seat 10.

In practical operation, motion is transmitted from the engine 3 by its shaft 9 to the shafts 5, through the instrumentality of the beveled pinions 8. If the rudder 23 and the rudder 14 are each in a vertical position, the craft will rise vertically. If the rudder 23 be swung from the position shown in Figure 3, the craft will move in the direction indicated by the arrow A, in Figure 2, or in an opposite direction. Similarly, if the rudder 14 be swung from the position shown in Figure 3, or in Figure 1, then the craft will tend to move in a direction indicated by the arrow B in Figure 1, the rudders, each, resolving out of the force which tends to lift the craft, a component which will move the craft laterally, or forwardly and backwardly as hereinbefore described.

It is obvious that motion may be transmitted to the rudder 14 by means of the shaft 12, the arm 15, the link 16, the lever arm 17, and the lever 18. Similarly, the wheel 28 and its shaft, the arm 26, the link 25, the arm 24 and the shaft 22 transmit motion to the rudder 23.

Having thus described the invention, what is claimed is:—

In a flying machine, a frame in the form of an inverted frusto-tetragonal pyramid; an engine mounted on the lower portion of

- the frame; a single propeller shaft journaled on each side of the frame and located midway between the front and the back of the frame, the shafts being disposed in up-
wardly diverging relation with respect to each other; means for connecting the lower ends of the shaft with the engine; a first rudder shaft journaled on the upper portion of the frame and located at right angles to a plane passing through the propeller shafts; a rudder located to the rear of the frame and carried by the first rudder shaft in parallel relation to the axis of said shaft; a second rudder shaft journaled on the frame and located below but closely adjacent to the first rudder shaft, the second rudder shaft being disposed at right angles to the first
- 5 10 15

rudder shaft and in alinement with the propeller shafts; a rudder located within the frame and carried by the second rudder shaft in parallel relation to the axis of said shaft; means for operating the rudder shafts from an inferior point; and lifting propellers carried by the propeller shafts and overhanging the frame, the propellers being spaced to expose the rudders.

In testimony that I claim the foregoing as my own, I have hereto affixed my signature in the presence of two witnesses.

FRANK HOFFNER.
